SKIRT MARKER

Barbara Holtz, Cleveland, Ohio

Application November 18, 1935, Serial No. 50,269

4 Claims. (Cl. 33—9)

This invention pertains primarily to a skirt marker by means of which accurate markings of hems and seams in ladies' skirts are assured. The invention is also adapted for use in other lines of the tailoring art such as men's trousers where accurate even seams are desired.

Another object of the invention is to provide an improved but simple means for clamping the marking chalk and the measuring stick to each other. The entire device can be economically produced making it easily available to the woman who does her own sewing.

Other objects and advantages will be apparent from the illustrations in the accompanying drawing, in which:

Fig. 1 is a view showing the manner of using the device.

Fig. 2 is an enlarged view of the marker with round chalk and yardstick in position.

Fig. 3 is an end view of the chalk holder showing the spring mechanism.

Fig. 4 is a top elevation with yardstick in section.

Fig. 5 is a section taken on line 5—5 of Fig. 3.

Fig. 6 is a perspective view of Fig. 4.

Fig. 7 is a side elevation with flat chalk, and yardstick in section.

Referring to the drawing; the chalk holder for the marking device consists of a concave elongated side portion 10 having a plurality of inwardly bent fingers or teeth 11 at the forward end and flanged wings 12 and 13 projecting at the edges of said side portion 10 and a concave elongated opposite side portion 14 also having flanged wings 15 and 16 projecting from the edges thereof.

A pivot pin 17 is journaled through the center of the outer wings 12 and 13 and the inner wings 15 and 16, a tension spring 18 being coiled thereon, the end 19 being bent in such manner as to press against the inner curved surface of the elongated portion 10 while the opposed end 20 is bent in a similar manner and presses against the

inner curved surface of the elongated portion 14.

In operation, the ends 21 and 22 of the side portions 10 and 14 respectively, are pressed together and a piece of round chalk or marking composition 23, flat chalk 23a or square chalk (not shown) 5 is placed between the down bent fingers 11 of the portion 10 and the end 24 of the portion 14 and a yardstick 25 or similar measuring device is superimposed over the chalk or marking composition 23 and the ends 21 and 22 of the top and bottom portions 10 and 14 respectively are released.

The device is set on the yardstick 25 as shown in Fig. 2 at the height from the floor that is desired to turn the hem 26 of the skirt 27. Both the chalk and the yardstick are held by jaws of the clip or clamp, which can be adjusted to any position desired.

By using the device in the manner shown, an absolutely even marking is assured.

I claim:

1. In a skirt marker, the combination with a measuring stick, of a chalk holder adjustable along the stick and comprising spring-pressed jaws clamping the stick and chalk against each other at the desired position.

2. The combination stated in claim 1, the holder having pivotally adjustable and oppositely recessed jaws between which the stick and chalk are clamped.

3. The combination stated in claim 1, the holder having a jaw concave on the inner side to hold the chalk and another opposed jaw recessed and provided with inwardly projecting teeth.

4. In a skirt marker, the combination with a measuring stick, of a spring clip chalk holder having jaws engaging the outer sides of the stick and chalk and clamping the same together, to hold the chalk at any desired elevation on the stick.

BARBARA HOLTZ.
